UNITED STATES PATENT OFFICE.

JOHN A. RUSH, OF GEORGETOWN, ONTARIO, CANADA, ASSIGNOR TO GEORGETOWN FOUNDRY AND MACHINERY COMPANY, LIMITED, OF GEORGETOWN, ONTARIO, CANADA.

KNITTING-MACHINE.

1,198,280.

Specification of Letters Patent. Patented Sept. 12, 1916.

Substituted for application Serial No. 18,783, filed April 2, 1915. This application filed July 22, 1916. Serial No. 110,792.

To all whom it may concern:

Be it known that I, JOHN A. RUSH, a subject of the King of Great Britain, residing in the village of Georgetown, county of 5 Halton, Province of Ontario, Canada, have invented certain new and useful Improvements in Knitting-Machines, of which the following is a specification, this application being filed as a substitute for my abandoned application, Serial No. 18,783, filed April 2, 1915.

This invention relates particularly to knitting machines of the circular type adapted to knit a tubular fabric in which periodic changes in the form or ribbing of the fabric produced are required to be made automatically. The particular embodiment of this type to which my improvements are applied uses vertical double-ended needles, 20 some operating from above and the others from below the knitting line, some of which needles require to be transferred at predetermined times to change their sphere of action from top to bottom or vice versa.

25 Important features of my invention are embodied in the means for supporting and transferring the needles.

Other features are the constructions and arrangements whereby I secure a simple and reliable machine capable of knitting hosiery with properly turned heel and toe.

The machine is hereinafter fully described and illustrated in the accompanying drawings in which—

35 Figure 1 is a front elevation of my improved machine; Fig. 2 a rear elevation of parts of the same; Fig. 3 a plan view with the knitting cylinders and upper parts of the machine removed; Fig. 4 a plan view of 40 parts of the machine showing more particularly the parts of the mechanism for returning needles into action during the latter half of the knitting of the heel and toe portions of a sock; Fig. 5 a side elevation of 45 part of the mechanism for effecting the rotary and oscillating rotary drive; Fig. 6 a rear elevation of part of the same; Fig. 7 a rear elevation of part of the drive mechanism; Figs. 8, 9 and 10 details of parts of 50 the automatic belt-shifting mechanism; Fig. 11 a vertical section of parts of the cylinders and cam walls showing the method of transferring needles from one cylinder to the

other; Fig. 12 a plan view showing more particularly the parts intermediate the two 55 cylinders; Fig. 13 a plan view partly broken away and partly in section showing the needle transferring cam of the upper cylinder and the cam for throwing half the needles out of action during the knitting of 60 the heel and toe portions of a sock; Fig. 14 a view showing in front elevation and separated the various cams of the cam drum; Fig. 15 a plan view of parts of the yarn take-up which comes into operation during 65 the periods of oscillating rotary movement of the cylinders; Fig. 16 an enlarged side elevation partly in section of the work feeding mechanism; Fig. 17 a development of the cams and grooves of the upper cam wall; 70 Fig. 18 a similar view of the cams and grooves of the lower cam wall; Fig. 19 a plan view of the rocking finger for throwing needles out of action one by one during the oscillating rotary movement of the 75 cylinders; Fig. 20 a detail in front elevation of parts of the means for putting needles in and out of action during the turning of the heel and toe portions; Fig. 21 a detail in side elevation of part of the 80 operating mechanism of the cam for putting the needles of one half the lower cylinder out of action prior to the turning of the heel and toe portions; Fig. 22 a plan view of part of the yarn take-up mechanism; 85 Fig. 23 a plan view of the parts shown in Fig. 21; Fig. 24 a detail in plan of part of the work feeding mechanism; Fig. 25 shows in side elevation the various needles and jacks employed in the machine; and 90 Fig. 26 a diagram showing the arrangement of the needles and jacks in the cylinders.

In the drawings like numerals of reference indicate corresponding parts in the different figures.

Referring particularly to Figs. 1, 2, 3, 4 and 5, 1 is the main shaft, which carries two driving pulleys 2 and 3. The pulley 2 will be clutch connected to the shaft as usual, 100 while the pulley 3 will be connected by means of a speed reducing gear contained within the pulley so that for the same belt speed, the drive of the machine will be much slower when the driving belt is shifted from 105 the pulley 2 to the pulley 3. As this ma

chine is of the type in which the rotary movement employed while knitting the top and leg of the sock is changed to an oscillating rotary movement during the knitting of the heel and toe portions, the change of speed is necessary. Any suitable speed reducing gear might be employed, and none is therefore illustrated as the employment of such speed changing gear is old in the art.

- 10 The countershaft 4 is journaled at the back of the machine, which shaft is geared by means of the bevel gearing 5 to the vertical shaft 6 journaled at the back of the machine. This vertical shaft, by means of 15 the gearing 7, drives the upper cylinder 8, and by means of the gearing 9 the lower cylinder 10, and by the gearing 11 the rotary disk 12 of the work feeding mechanism.

The countershaft 4 is given either a continuous rotary or an oscillating rotary movement from the shaft 1 by the following mechanism. On the shaft 1 is secured a sprocket wheel 13, which by means of a suitable sprocket chain drives the sprocket 25 wheel 14 suitably journaled on the frame. Suitably connected with the sprocket wheel 14 is the sprocket wheel 15, which by means of a suitable sprocket chain drives the sprocket wheel 16 suitably journaled on the 30 frame of the machine. Suitably journaled and connected with the sprocket wheel 16 is the sprocket wheel 17 which by means of a suitable sprocket chain drives the sprocket wheel 18, which is secured to a clutch member 35 19 loose on the countershaft 4. If this clutch member 19 be given a driving connection with the shaft it is evident that the latter will be given a continuous rotary movement as long as the main shaft is continuously driven.

The oscillating rotary movement of the shaft is effected through the following mechanism: A clutch member 20 loose on the countershaft 4 has a sprocket wheel 21 secured thereto. A sprocket chain 22 runs on this sprocket wheel 21 and also around a sprocket wheel 23 suitably journaled at the front of the machine. The sprocket wheel 16, (see particularly Figs. 3 and 5), carries 50 a headed pin 24, the head of which is adapted to slide in guides 25 formed on the bar 26 which is adapted to slide on the parallel guide rods 27, (see particularly Fig. 5.) This sliding bar 26 is suitably secured at 28 55 to the sprocket chain 22. The result of this construction is that the rotary movement of the sprocket wheel 16, which is continuously driven is transformed into a reciprocating movement of the bar 26, which imparts a similar movement to the chain 22, which consequently imparts an oscillating rotary movement to the sprocket wheel 21 and the clutch member 20 to which it is connected.

The nature of the drive imparted to the 60 countershaft 4 depends on which of the

clutch members 19 and 20 is given a driving connection with the shaft. The driving connection of either of these with the shaft is effected by means of the clutch member 29, which as usual is slidable on the shaft 70 but is rotatable therewith. If this clutch member be shifted to the right to engage the clutch member 19 (see Fig. 3) the countershaft will be given a continuous rotary movement. If it be shifted to the left to engage the clutch member 20, the countershaft will be given an oscillating rotary movement.

Arrangement of the work feeding mechanism.—Before considering the parts of the 80 mechanism specially connected with the knitting operation, I will first describe the auxiliary mechanisms of the machine, and at this point it will be convenient to set out the construction and arrangement of the work feed mechanism, which, as previously set out, is driven from the vertical shaft 6 by means of the gearing 11, and is supported on the disk 12.

The disk 12 is suitably journaled on the 90 plate 30 around the edges of an opening therein, the disk itself also having an opening as usual for the passage of the work. On the disk standards 31 are journaled the feed rollers 32, one of which is pressed toward the other by means of spring actuated plungers 33 such as commonly employed for similar purposes (see Fig. 16). These rollers at opposite ends are geared together by means of the pairs of intermediate gears 95 34. This arrangement permits of the separation of the rollers as widely as may be necessary without interfering with their drive.

One of the rollers at one end carries the 105 gear wheel 35, which meshes with the gear wheel 36 on the shaft 37 journaled on the standards 31, and having secured thereto intermediate its ends a worm wheel 38. This worm wheel meshes with the worm 39 110 vertically journaled on the disk 12, and having secured to its lower end a gear pinion 40. This gear pinion meshes with the internal annular gear wheel 41, which is loosely journaled on top of the plate 30 and 115 is frictionally held so that normally it does not rotate, a brake frictionally holding the internal gear wheel 41 from rotating; as shown more particularly in Figs. 3 and 16.

42 is a brake shoe suitably guided on the 120 frame 43 and having the rod 44 secured thereto and extending through an opening in the outer end of the frame 43. The outer end of the frame is counterbored and a plug 45 is screwed therein through which the rod 125 44 passes. A coil spring 46 surrounds the rod 44 and bears against the brake shoe 42 and against the plug 45. The brake shoe is thus spring pressed against the outer rim of the internal gear 41, and the tension of the 130

spring can be varied by screwing the plug 45 in or out.

From the arrangement described it follows that as the disk 12 is rotated, the feed rollers 32 are likewise rotated. If for any reason the feed of the rollers is faster than the speed of knitting, the internal gear wheel may slip. Suitable tension will be thus kept on the work without undue strain, and the degree of tension may be readily regulated by adjusting the plug 45.

To enable the work to be pulled back for examination when necessary, the gear wheel 35 instead of being secured to the spindle 15 of its roller 32 is loose thereon and is connected therewith by means of a ratchet clutch. Part 194 of the clutch is formed on the gear wheel and the movable part 195 is slidable on a feather key on the spindle. 20 The parts of the clutch are normally yieldingly held in engagement by the coil spring 196, which bears against the clutch member 195 and a collar 197 secured to the end of the spindle of the roller.

25 *Control mechanism.*—The control of the needles to effect the desired changes of needles during knitting is obtained by means of the following mechanism: A cam drum 47 is secured to a shaft 48 suitably journaled on one side of the machine. On the same shaft is also secured the drum 49. These drums are provided with cams to effect various movements as hereinafter described.

The shaft 48 is actuated by the following mechanism: A shaft 50 is geared to the main shaft 1 by means of the bevel gearing 51. The shaft extends toward the front of the machine and has the cam 52 secured thereto. A connecting rod 53 is provided 40 with the forked end 54 embracing this cam as shown, so that an endwise movement of the connecting rod toward the left of Fig. 1 is effected by the rotation of the cam. The return movement is effected by means of the 45 coil spring 55, one end of which is secured to the connecting rod and the other to the frame of the machine. This connecting rod 53 has its other end pivoted to the link 56 connected to the spindle 57 journaled parallel and adjacent to the shaft 48. A dog 58 is journaled on the same pivot as the connecting rod 53 so that the dog partakes of the same movements as the connecting rod. The dog 58 rides on the teeth of a ratchet 55 wheel 59, which is loosely journaled on the end of the shaft 48. Through the medium of the dog 58 an intermittent movement of the ratchet wheel is obtained, each rotation of the shaft 50 causing the ratchet wheel to move the distance of one tooth.

60 A sprocket wheel 60 is suitably connected to the ratchet wheel 59 so as to rotate therewith. On this sprocket wheel is hung the sprocket chain 61, the lower end of which 65 may be guided by means of the idler 62.

This sprocket chain has cam lugs 63 projecting therefrom at predetermined positions. Riding on the sprocket chain is one end of the bell crank lever 64 suitably pivoted on the frame of the machine. The other end of this bell crank lever has the finger 65 pivoted thereon, the other end of which is in a position to be engaged and lifted by any one of a series of pins 66 secured to the side of a ratchet wheel 67, which is secured to the shaft 48. The pins correspond in position to the cam lugs 63. With this ratchet wheel the dog 68 is adapted to engage, this dog being pivoted on the same pivot as the dog 58. The end of this dog 68 is sufficiently broad to rest on the end of the finger 65 when the latter is raised by one of the pins 66, as shown in Fig. 1. While in this position, as the connecting rod 53 reciprocates, the dog 68 moves idly back and forth on top of the finger 65. As soon, however, as one of the lugs 63 passes beneath the end of the bell crank lever 64, the finger 65 is drawn back and falls off the pin 66 with which it is engaged, thus allowing the dog 68 to engage the ratchet wheel 67. As the dog 68 is reciprocated it moves this ratchet wheel 67 one tooth at a time until the next pin 66 raises it to the position illustrated, when the movement of the ratchet wheel, and consequently of the drums 47 and 49, stops.

65 *Change of motion and speed reduction.*—The movement of the clutch member 29 which controls the changes from rotary to oscillating rotary movement of the countershaft 4 is effected from the cam drum 49 by the following means: A sliding bar 69 is suitably supported at the rear of the machine adjacent the countershaft 4. This sliding bar has secured thereto the clutch shifter 70, which engages the sliding clutch member 29 in the usual manner. The sliding bar 69 also has secured thereto a pair of arms 73 at different levels, as seen more particularly in Fig. 1. A pair of cam projections 71 are secured on a sleeve 72 longitudinally movable on but rotatable with the vertical shaft 6. A suitable feather-key connection is all that is necessary for this purpose. It is evident that by shifting this sleeve that the cam projections 71 may be brought into position to engage either one of the arms 73 and that the sliding bar 69 will be moved in one direction or the other to engage the clutch member 29 with either one or other of the clutch members 19 and 20. The sleeve 72 is moved by means of the shifter lever 74, one end of which is adapted to engage with the shifter in the usual manner, while the other end lies in the path of the cam projections 75 on the drum 49.

70 Each time a cam projection passes under the end of the arm 71, the lever is rocked to raise the sleeve 72 to cause the cam projec-

tion 71 thereon to come into a position to engage the lower arm 73 and thus move the bar 69 to cause the shifter 70 to throw the sliding clutch member 29 into engagement 6 with the clutch member 20, thus effecting an oscillating rotary drive of the cylinders.

After one of the cam projections has passed from under the end of the lever 74, the latter returns to its normal position, 10 and the sleeve 72 is moved to restore the parts to their normal position in which the clutch member 29 is in engagement with the clutch member 19 and continuous rotary movement is imparted to the cylinders.

15 During the times of oscillating rotary movement of the cylinders, it is necessary, as before stated, to reduce the speed of the drive, which is effected by shifting the driving belt from the pulley 2 to the pulley 3: 20 This shift is effected by the following mechanism: A belt shifter 76 is adapted to slide on the rods 77 suitably secured to the frame of the machine. This belt shifter is provided with the shifter fingers 78. Mounted on the 25 shifter are two plungers 79, each preferably formed with an enlarged cylindrical head 80. These plungers are reduced in diameter below their upper ends, as shown particularly in Fig. 9, forming shoulders. Against each 30 shoulder bears a coil spring 81, the other end of which bears against a shoulder formed at the lower end of the cylindrical hole in the plate in which the plunger slides. These coil springs normally tend to raise the 35 plungers to project their upper ends above the surface of the shifter. If either of the plungers be depressed so that its upper end is substantially flush with the upper surface of the shifter, its head 80 will be projected 40 into the path of the cam 82, which is secured to the countershaft 4. This cam is shaped in plan as shown most clearly in dotted lines in Fig. 8. One side of the cam will therefore engage one plunger and the other side 45 the other plunger if the plunger be pushed down sufficiently far to bring its head into proper relationship to the cam. The shifter will thus be moved to one side or the other according to which plunger is depressed.

50 The plungers are depressed by the following mechanism: The slide 83 is mounted in suitable guide ways to slide on the shifter 76. Suitably mounted on this slide are the inclined planes 84 facing in opposite direction and somewhat offset so that when one is moved to depress one plunger, the other clears the opposite plunger and allows it to rise. The slide is moved longitudinally to actuate the planes, and consequently the 55 plungers, by means of the rock shaft 85, to which is secured the rock arm 86 pivotally connected by means of the pin 87 with the outer end of the slide 83. This rock shaft 85 is suitably journaled on the frame of the 60 machine and its other end carries the rock

arm 88, which is preferably provided with an anti-friction roller 89, which lies in the paths of the cam projections 90 on the cam drum 49. These cams are arranged to alternately push the rock arm 88 to one side or the other, thus rocking the shaft 85 and effecting the shifting of the belt through the medium of the mechanism already described. These shifts are timed to occur at the times of changing from continuous rotary to oscillating rotary movement and vice versa, and also while needles are transferring, as hereinbefore set out.

Arrangement of the knitting cylinders, needle shifting devices and cams.—The cylinders 8 and 10 are provided with alined vertical grooves 91 in which grooves the needle jacks 92 and non-transferring needles are adapted to slide, (see particularly Figs. 11, 12, 13 and 25). Certain of these jacks are adapted to carry the double-ended needles 93. The needle-carrying jacks are provided with the heels 94 and 95, the heels 94 being adjacent the needle-engaging ends of the jacks and the heels 95 adjacent the butt ends of the jacks. The heels of the needle-carrying jacks run in the cam grooves of the cam walls 96 and 97 surrounding the cylinders as shown, as do the heels of the non-transferring needles 95 as hereinafter described.

The following is the arrangement of the needles and jacks in the cylinders, which arrangement is indicated diagrammatically in Fig. 26: The right hand side in this figure shows the arrangement of the needles of the front halves of the cylinders, and the part to the left the arrangement of the needles of the back halves of the cylinders. It will be noted that in the upper cylinder alternate grooves are fitted with jacks *b*. These jacks carry no needles, but are provided with the projecting fingers 100 the same as the needle-carrying jacks. These projecting fingers form latch guards for the needles of the lower cylinder operating in grooves alined with the grooves in which the jacks *b* operate.

At the back half of the upper cylinder between the grooves occupied by the jacks *b*, the jacks *g* and *h* are alternated, the difference between the two jacks being that the heels 95^a are longer than the heels 95^b for a purpose which will hereinafter appear. At the front of the cylinder the grooves alternating with those occupied by the jacks *b* are alternately provided with the jacks *c* and the single ended needles *a*. The jacks *c* are provided with the long heels 95^c, while the needles *a*, which do not transfer are not provided with heels corresponding to the heels 95, but only with the heels 94.

In the lower cylinder, in the front half of the cylinder the arrangement of the jacks and needles is as follows: first a jack *b*, then 130

a non-transferring needle *d*, then a jack *f*, then a non-transferring needle *d*, then a jack *b* and so on. In the back, the arrangement is first a jack *g*, then a needle *e*. The jacks *b* are of course employed opposite non-transferring needles *a* of the upper cylinder. The non-transferring needles *d* and *e* are each provided with lower heels *95* and with the upper heels *94*, as are also the jacks *f* and *g*, the difference being that in the needles *d* and jacks *f* the heels are longer than in the needles *e* and jacks *g*, the longer heels being, it will be seen, at the front half of the cylinder so that the non-transferring needles and the jack-carrying needles may be thrown out of action for one half the circumference of the lower cylinder as herein-after appears.

- 20 Each jack is provided with a hook *98* adapted to hook over the hook of a needle. Facing the hook is the shoulder *99* sufficiently spaced therefrom to allow the hook *98* to move to a position over the hook of the needle. Beyond the hook the ends of the jacks are extended as fingers *100* of less width than the main part of the jack. A jack disengaging ring *101* is supported between the two cylinders on an annular plate *102*, which is mounted to oscillatably rotate on the collar *103* carried by the lower knitting cylinder, (see particularly Fig. 11.) Both the upper and lower edges of this disengaging ring, it will be noted, are beveled inwardly so that when a jack is pressed up its end will engage and ride out over this ring, as shown in the lower part of Fig. 11, thus disengaging the hook *98* from the hook of the needle. The shoulder *99* still engages the end of the needle as the jack is pushed up and thus forces the hook at the other end of the needle to ride by the hook *98* of the upper jack until the hook of the needle passes behind it and the latter is free to be drawn inwardly to engage beneath the hook of the needle. The jacks between the heels are relieved or cut away at *194* on a taper to allow them to rock sufficiently without interference with the cam walls *96* and *97*.
- 50 The jacks are yieldingly pressed inwardly by means of the coil springs *104* drawn tightly around the lower end of the upper cylinder and upper end of the lower cylinder outside the jacks. Thus by moving any given jack toward the opposite cylinder, any given needle may be pushed up to be engaged by the aligned jack of the opposite cylinder. The fingers *100*, it should be noted, serve also as latch guards for the needles of the lower cylinder operating in grooves aligned therewith. The means for effecting this endwise movement of the jacks at a given time will now be described. The cam walls of which developments are shown in Figs. 17 and 18 are provided with grooves

in which the heels *94* and *95* of the jacks travel. Referring particularly to Fig. 17, which is a development of the cam wall of the upper cylinder, *105* is what may be termed an intermediate groove. In part of this groove, the upper heels of jacks carrying needles which are knitting and the upper heels of non-transferring needles run prior to reaching the knitting point. A similar groove *106* is provided for the heels *94*.

107 and *108* are the knitting cam grooves, knitting taking place while the heels of jacks and needles are passing through the portions *109* and *110* of the grooves in which the jacks, and consequently the needles carried thereby, as well as non-transferring needles are drawn farthest away from the knitting line.

Parts of the grooves *105* and *106* form 85 by-paths past the knitting cam grooves. The jacks are guided so that their heels travel along either the knitting grooves or the by-paths by means of the inclined cam *111*, which is movable to and from the position to engage the heels *94*. Preferably the movement is radial, (see Fig. 13). When pushed forward to the position shown in full lines in Fig. 13, the cam *111* will engage the heels *94* so as to guide them up into the groove 95 *108*. When the cam is withdrawn to the position shown in dotted lines in Fig. 13, the heels *94* do not engage the cam and the heels *94* and *95* will travel through the by-paths formed by the grooves *105* and *106*. 100 It will be noted that after the jacks have been moved to the knitting position by the portions *109* and *110* of the knitting cam grooves, that they are returned to the grooves *105* and *106*, so that the cam *111* has 105 absolute control of the jacks to send them with their heels in either the intermediate or the knitting grooves.

The cam *111* is operated in a manner and at such times as hereinafter described. The 110 intermediate cam groove *105* has a cam *112* located therein at a position intermediate the portion *109* and the position occupied by the cam *111* and movable to and from a position to engage the heels *95*. This cam 115 is arranged to throw down the heels of jacks traveling in the non-knitting groove *105* sufficiently far to cause the jack or jacks so moved downward to transfer their needles to corresponding jacks of the lower 120 cylinder. After passing down the cam *112*, the heels *95* travel along the path *113* a short distance to give time for the transfer of the needles, and then pass up the inclined plane *114* back to the non-knitting cam groove *105*. 125

In line with the path *113* and the inclined plane *114*, the under side of the groove *105* is cut away as indicated at *115* to enable the heels running in the groove *105* to pass clear of the groove during the changing of 130

the needles. Jacks so moved down remain down until the needles are retransferred from the lower cylinder, when they are pushed up by the needles to bring their heels 5 again into alinement with the grooves 105 and 106.

The cam wall of the lower cylinder of which a development is shown in Fig. 18 is provided with a non-knitting groove 116 and a non-knitting pathway 117 in which the heels of the jacks and needles of the lower cylinder may run. The pathway 117 need only be a rib on which the heels may rest and not necessarily a groove, as the 15 weight of the jacks and needles tends to hold heels on the rib.

118 and 119 are knitting cam grooves, each provided with two knitting cams, both of which are operative during the oscillating rotary movements of the cylinders and only one during the continuous rotary movement of the cylinders as is common in circular knitting machines. These knitting cams are respectively numbers 120, 121, 122 25 and 123.

The pivoted gate 124 forms the control which determines which of the pairs of knitting grooves is operative. When the jacks are traveling from the direction indicated 30 by arrow, the heels traveling in the groove 119 will, if the gate be in the position shown in dotted lines, strike the said gate and move it to the position shown in full lines, thereafter traveling down around the knitting cam 120. When, as occurs during the periods of oscillating rotary movement, the jacks travel alternately in opposite directions along the groove 119, the cam is rocked from one side to the other by the heel of the 40 leading jack, so that pairs of knitting cams 120—122 and 121—123 become alternately operative.

The lower cam wall is also provided with a movable inclined cam 125, which is so 45 placed that it may be engaged by the heels of jacks passing around the groove 118. This cam 125 is movable radially to and from a position to engage the heels of jacks in a similar manner to the cams 111 and 112 50 as hereinafter more particularly described.

The cam 125 is located in alinement with cam 112 as the shifting of needles takes place at the same position toward the back of the machine for either cylinder. The jack heels 55 passing up the inclined cam 125 travel along the path 126 a sufficient distance to give the needles time to transfer. The heels then travel down the inclined plane 127, which restores the jacks to their normal position 60 after transferring, with their heels in alinement with the non-knitting groove 116 and pathway 117.

Before describing the manipulation of the jacks and needles during the knitting of the 65 toe and heel portions of the sock, it will be

well to describe the method of operation of the parts already described for the transfer of needles from one cylinder to the other.

It will be assumed that a sock is to be knitted with a one-and-one rib top, a three-and-one rib in the leg, plain heel, plain sole portion and a three-and-one rib instep. 70 It will also be assumed that the sock is of a size to require seventy-two needles. The cycle of operations starts with the one-and-one rib. 75 This means that 36 needles are in the upper cylinder and 36 in the lower cylinder, the arrangement being alternate. The jacks *g*, see Fig. 25, for alternate needles of the 36 in the upper cylinder are provided with long 80 heels, which are indicated by the reference numeral 95^a (see Figs. 13 and 25). The remaining jacks *h*, see Fig. 25, for one-half of the circumference of the upper cylinder are provided with shorter upper heels indicated 85 by the reference character 95^b. The jacks of needles for the remaining one-half of the cylinder which alternate with the jacks carrying the heels 95^a are without upper heels at all, or heels too short to be engaged by the 90 cam 112.

If therefore when the cylinders are in continuous rotation knitting the one-and-one rib, the cam 112 is pushed into the position shown in full lines in Fig. 13, the heels 95^a 95 will be engaged by the cam and their jacks carried down to transfer the needles carried thereby to the lower cylinder as hereinbefore described. This results in alternate needles of the upper cylinder being transferred to the lower cylinder, leaving eighteen needles in the upper cylinder and giving fifty-four needles in the lower cylinder. This results in the knitting of a three-and-one rib. This knitting goes on until the heel is reached. The cam 112 is then pushed into the position 100 shown in dotted lines in Fig. 13. This engages the upper heels 95^b and results in all the remaining needles for one-half of the circumference of the upper cylinder being transferred to the lower cylinder, making plain knitting for one-half the circumference of the sock, the three-and-one rib being continued through the remainder of the circumference as nine needles *a* (see Fig. 25) 105 still remain in the upper cylinder. The jacks which have been transferred remain in non-knitting position until restored by the push of the opposite jacks when needles are being re-transferred. The turning of the heel now 110 commences as will be hereinafter described, the nine remaining heels in the upper cylinder being held out of action by the withdrawal of the cam 111. During and after the turning of the heel, the position of the needles remains unchanged, nine only remaining in the upper cylinder, these being 115 returned to action after the heel is turned by the cam 111 which is returned to normal position. When the toe is reached the turn- 120 125 130

- ing again commences as hereinafter described, and, after turning, the cam 125 is pushed in sufficiently far to engage the heels of the jacks *f* and *g*, see Fig. 29, of the lower cylinder, restoring the necessary needles to the upper cylinder to enable the knitting of a one-and-one rib to be commenced, after which the cycle of operations commences over again. As there is no need for a selective transfer of needles from the lower cylinder to the upper, the heels 95 of the jacks of the lower cylinder of needles which have to be transferred may be all of the same length.
15. *Turning of the heel and toe.*—The turning of the heel and toe is effected by means of the following constructions: Between the knitting cams 121 and 123 a dog 128 is pivoted, the end thereof being notched in such a way that no matter what position shown in Fig. 18 the dog occupies, it will be in a position to catch the heel of any jack traveling along the groove 118, assuming the dog to be pointed toward the direction in which the jack is traveling. The dog rests against the corners of the blocks forming the grooves and cam paths as shown.
- On reference particularly to Fig. 20, it will be seen that the pivot 150 of the dog 128 has a lug 151 secured thereto. To this lug is secured one end of a coil spring 152, the other end of which is secured to a suitable stationary part. The point of connection of the spring is so located that as the dog 128 rocks the coil spring crosses from one side to the other of the center of the pivot so that the single spring will tend to yieldingly hold the dog 128 in either of the positions shown in Fig. 18.
40. Between the cams 120 and 121 a finger 129 is journaled. This finger is provided with a forked end 130 of sufficient width to engage the heels of two adjacent jacks. This finger is so proportioned and located that when rocked from one side to the other it will engage the lower heels of the two jacks and draw the jacks down sufficiently far to draw their upper heels down past the pivoted gate 124 and down into the groove of the cam 120, assuming the initial position to be that shown in full lines in Fig. 18. If the initial position be that shown in dotted lines, the movement is in the reverse direction, and the upper heels of the jacks are carried down the groove of the cam 121.
- Above the gate 124 a gap 131 is formed in the path 117 to permit of the heels of jacks passing from the groove 119 to the path 117 and vice versa. A similar gap 132 is formed in the dividing rib between the grooves 116 and 118 to permit the passage of the lower heels from the groove to the groove 116 and vice versa.
45. To the right of the knitting cam 121 will be seen a pivoted cam finger 133 which may be rocked up or down to move jacks from engagement with the non-knitting grooves to the cam grooves and vice versa. During the turning of the heel and toe, the knitting cylinders are oscillating and only one-half of the needles of the lower cylinder are in operation. The remaining half must therefore be thrown out of operation. This is effected by rocking the cam finger 133 to the position shown in dotted lines in Fig. 18.
- The jacks for one-half of the circumference of the lower cylinder are provided with elongated upper heels 94^a so that when the finger 133 is moved to the position shown in dotted lines, only the jacks carrying these elongated heels are raised to run on the non-knitting pathway 117, the remainder, except as hereinafter described, continuing to run in the knitting grooves 118 and 119.
- A gap 134 is formed in the rib separating the grooves 116 and 118 immediately below the finger 133 to permit of the lower heels of the jacks raised by the finger 133 passing from one groove to the other. When the finger is raised to the elevated position, it will engage the elongated heels of the previously raised jacks and re-transfer them to the knitting cam grooves. The means for effecting the movements of the cam finger 133 will be hereinafter described, and also the means for actuating the finger 129. A guard 135 is located over the gap 131 to prevent jacks lifted by the dog 128 from throwing up too far, the upper heels of these jacks engaging said guard.
- The mode of operation of the parts described is as follows: During the continuous rotary movement of the cylinders, the jacks move in the direction indicated by the arrow, the gate 124 being in the position shown in full lines and the dog 128 in the position shown in dotted lines. The heels of each jack then pass along the grooves 118 and 119. The cams 120 and 122 are then active in knitting.
- As soon as the oscillating rotary movement begins, all the knitting is done in the lower cylinder and all the needles in the upper cylinder must then be idle. To effect this the cam 111 is withdrawn so that the 115 heels of the upper needles *a* (Fig. 13) are no longer directed up to the groove 108, but are allowed to travel in the groove 106, which maintains them idle. The pivoted cam finger 133 is at the same time operated 120 to throw the needles of one-half of the circumference of the lower cylinder into inoperative position. The heels of the jacks and needles *e* and *g* (Fig. 26) remaining in the lower cylinder then reciprocate in the 125 grooves 118 and 119. Each time, however, a change in the direction of movement takes place, the heel of the first jack or needle traveling in the groove 119 is engaged by the dog 128 which automatically rocks up 130.

ward under the pressure exerted by the heel, and thus raises the jack or needle sufficiently high to bring the lower heel into a position to travel in the groove 116 while the upper heel is lifted past the gate 124 to ride in the pathway 117.

Assuming the original position of the dog to be that shown in full lines in Fig. 18, it now drops over to the position shown in dotted lines ready to catch the heel of the first jack or needle which reaches it after the direction of movement of the jacks has changed. The end needles of those which are knitting the heel are thus thrown out of action one by one. It will be noted of course that the gate 124 alternately changes its position as contacted by jack heels so that the gap for the passage of the upper heels of jacks raised by the dog 128 is always in the right position. When the wheel is half turned, about half a dozen needles are still knitting. It is now necessary, to complete the turning of the heel, to begin to throw the needles into action again until the needles for one-half of the full circumference of the lower cylinder are again knitting. This is effected by means of the finger 129.

Assuming the finger to be in the position shown in full lines in Fig. 18, the jacks are traveling in the direction indicated by the arrow. As soon as the leading two jacks having their lower heels running in the groove 116 reach the proper position, they engage the finger 129 which has been rocked by means hereinafter described into their path, and the two jacks continue the rocking and are moved down by the finger. The gate 124 will then be in the position shown in full lines, and the upper heels, as the jacks are forced down by the finger 129, will be engaged by the under side of the gate and travel down past the gate and down the cam 120, while the finger 129 swings into the position shown in dotted lines.

It will be noted that the finger 128 has been previously rocked to the position shown in dotted lines by its engagement with the first of the jacks still in the knitting position, so that it lies in the path of the lower heels of jacks being moved down to a knitting position by the combined action of the finger 129 and the gate 124. A notch 136 is therefore formed in the side of this dog, see particularly Fig. 19, which permits of the passage of the heel down past the knitting cam 122. The result of this arrangement is that during each movement of the knitting cylinders in either direction one needle is thrown out of action and two brought into action, a gain of one thus being made at each movement. This gain continues until all the needles are again in action, when the movement of the finger 129

ceases and the continuous rotary movement of the cylinder is resumed.

The process described of again bringing the needles into action after they have been thrown out of action in the turning of the heel is of importance, as it prevents objectionable holes along the sides of the heel along the line of the turn.

After the turning of the heel or toe portion the continuous rotary movement of the cylinders recommences with all the needles in action, the cam 111 and the cam finger 133 being moved, as hereinbefore set out, to restore the needles to their proper knitting positions for the foot after the heel is turned. 80

Control mechanism for movable cams and cam fingers.—The cams of the cam drum 47 are shown particularly in Figs. 3, 4, and 14. The cam projections 137 on the drum 47 serve to actuate the lever 138 fulcrumed on the spindle 57 (see particularly Fig. 2). The other end of this lever is so positioned that it may engage and push the projection 139 on the ring 140, thus turning the ring slightly to the right in Fig. 4. On this ring 140 is pivoted the rocking pin 141 which is yieldingly held so that it projects radially by means of two coil springs 142 connected to opposite sides of the rocking pin and the ring 140. Normally this pin is out of the path of a cam projection 143 secured to the vertical shaft 6. When, however, the ring is pushed to the right, the pin comes into the path of the cam projection 143 so that the ring will be moved each time the cam projection oscillates from one side to the other as it does during the oscillating knitting movements of the cylinders. The ring is thus given a short oscillating rotary movement, the amount of which is determined by one of the two stops 144 connected to the top of the frame of the machine and extending into the path of the projection 145 on the ring and by the projection 139 engaging the end of the lever 138. 110

When the movement of the ring is stopped by the projection 145 engaging one of the stops 144, the cam projection 143 slips by the rocking pin 141, which, as before stated, is only yieldingly held by the springs 142. The cam projection thus passes by the pin and is positioned to engage it on the opposite side for the return movement. 115

When oscillating rotary movement of the knitting cylinder ceases, the cam projection 137 releases the lever 138 so that the ring will be moved sufficiently far by the last oscillating movement of the cam projection 143 to clear the path of the cam projection, the other stop 144 limiting the movement, and the cam projection thereafter rotates continuously without contacting with the rocking pin 141. It will be noted that 120

125

the projection 145 has a cavity formed therein which engages the lower end of the rocking arm 146, which actuates the rocking finger 129, see Figs. 1 and 20. This rock arm 146 is loosely journaled on the pivot of the finger 129 and on the pivot of the finger 129 is secured a lug 147. The arm 146 has two projections 148 formed thereon, one at each side of the lug 147 and spaced therefrom. A coil spring 149 is secured to the lug 147 and to the arm 146, so that as the finger 129 rocks from one side to the other the coil spring will cross from one side to the other of the center on which the finger rocks. From this construction it follows that when the rock arm 146 is moved to the left, having reference to Fig. 20, the left hand projection 148 will engage the lug 147 to push the latter to the right to move the finger 129 into the path of the heels of the jacks as hereinbefore described. The jacks continue the movement of the finger until the spring 149 crosses the center, when the tension of the spring will snap the lug 147 and with it the finger 129 to the limit of its motion to the right and therefore to a position in which when the rock arm 146 is moved in the reverse direction the lug 147 will be engaged by the right hand projection 148 and the reverse movement started to be continued by the heels of the jacks until the spring again crosses back past the center and the lug 147 and finger 129 are snapped back to the left. A comparatively limited movement of the ring 140, it will be seen, is sufficient to effect the preliminary movements of the finger 129.

On the drum 47 I also form cam projections 153. These cam projections are adapted to engage one end of the bent lever 154 journaled on the spindle 57. The upper end of this lever is pivotally connected with one end of the connecting rod 155. The other end of this connecting rod is pivotally connected to one end of a bell crank lever 156 suitably fulcrumed on a bearing 157 secured on the cam wall of the upper cylinder. The other end of this bell crank lever is connected by means of a pin and slot connection with the outer end of a slide rod 158 adapted to slide through a suitable bearing connected with the said cam wall. The inner end of this slide rod carries the cam 122. A coil spring 175 bears against a shoulder of the bearing of the slide rod and against the bell crank lever 156, thus tending to withdraw the cam from its operative position. The function of the cam projections on the drum 47 is therefore only to move the cam inwardly toward the knitting cylinder, the reverse movement being effected by the spring.

It will be noted on reference particularly to Fig. 14 that one of the cam projections 153 is lower than the other. Consequently

one of the cam projections causes the cam 65 112 to be projected toward the upper knitting cylinder a less distance than the other cam, and consequently the cam may be caused to first engage the long heels 93^a of the upper jacks and substantially the 70 shorter heels 93^b as hereinbefore described to effect progressive transfer of needles from the upper to the lower cylinder.

The drum 47 also has formed thereon the cam projection 159. This cam projection 75 is adapted to engage one end of a bent lever 160. The other end of this lever is pivotally connected with one end of a connecting rod 161, the other end of which is pivotally connected with a bell crank lever 162. This bell crank lever operates the movable inclined cam 125 through the medium of similar parts to those carrying and operating the cam 112 as illustrated particularly in Fig. 13, which may be referred to 85 as illustrating the preferred construction for actuating the cam 125.

On the cam drum 47 I also form the cam projection 163 adapted to engage one end of a bent lever 164 fulcrumed on the spindle 57. The other end of this lever is pivotally connected with one end of a connecting rod 165, the other end of which is pivotally connected with a rock arm 166 secured to the spindle 167 forming the pivot of the pivoted cam finger 123. The pivoted cam finger may thus be rocked as hereinbefore described.

There is also formed on the cam drum 47 a cam projection 168 having two gaps 169 formed therein. This cam projection 168 engages one end of the bent lever 170, the upper end of which is pivotally connected with the connecting rod 171. The other end of this rod is pivotally connected with one end of a slide rod 173 suitably supported to slide on the upper cam wall and carrying at its inner end the inclined cam 111. During the periods of continuous rotary knitting this cam 111 is held in operative position. At the periods of oscillating rotary knitting, the gaps 169 allow the lever 170 to rock to permit the cam 111 to be withdrawn by the action of the spring 174 to allow jacks of the upper cylinder to follow the non-knitting grooves instead of the knitting cam grooves as hereinbefore described. This spring 174 will be arranged in the same manner as the spring 175 shown in connection with the slide rod 158 at the upper part of Fig. 13.

Yarn take-up mechanism.—During the periods of oscillating rotary knitting, the yarn necessarily slackens during the intervals which occur between the time of change of movement and the commencement of knitting. It is necessary to provide take-up mechanism for this purpose. The yarn is led through the yarn guide 176 suitably sup-

ported from the upper cylinder, after passing through an eye formed at the end of the take-up arm 177, which is fulcrumed intermediate its ends on the bracket 178 suitably supported on the frame of the machine. The yarn before passing through the eye on the take-up arm passes through an eye at the end of the tension lever 179. From the top the yarn passes over the yarn support 191 (81) through the eye 186 and thence to the eye on the tension lever 179.

During the periods of continuous rotary knitting the parts are in the position shown in Fig. 1. During the periods of oscillating rotary knitting, the parts assume the position now to be described and by means of the following mechanism: An arm 182 is pivoted on the spindle 57 and its upper end is adapted to ride on the cam projection 183 in which are formed the two gaps 184 corresponding in position with the gaps 169 in the cam projection 168. To the arm 182 is connected the lower end of the slide rod 185, the upper end of which is suitably guided in the bracket 178. When the gap comes beneath the end of the arm 182 the slide rod 185 drops at its upper end and clears the path of the end 186 of the take-up arm 177 with which it is engaged. As this end 186 is provided with a tension spring tending to throw down the end 186, the other end of the take-up arm flies up. In so doing it cocks the tension lever 179 and causes its end 195 to frictionally grip the yarn ag. inst the upper side of the bottom of the support of the tension lever. As this tends to prevent the drawing of yarn from the cop, the take-up arm will take up any slack in the yarn between the knitting point and the tension lever. The tension of the tension lever, however, is not sufficiently great to prevent the yarn being freely drawn from the cop as needed in the process of knitting. The spring actuating the take-up arm is best shown in Fig. 13. The take-up arm is journalled, it will be seen, on the pin 191 on which is secured the collar 192. The coil spring 193 has one end secured to the said collar and the other to the take-up arm. The spring, being normally under tension, tends to throw up the take-up arm as hereinbefore described.

Arrangement of the sinkers and latch guards.—The sinkers are carried by the collar 163, but as the arrangement and operation of the sinkers forms no part of the present invention they are not shown or described.

It will be noted that the annular plate 102 is supported on the collar 103 so that it may have an oscillating rotary movement thereon. This oscillating rotary movement is limited by means of the adjusting screws 187 which are screwed through projections on the plate 102 and are adapted to engage a

stop 188 secured to the lower cam wall, as shown more particularly in Figs. 2 and 12.

As the collar 103 on which the annular plate is supported rotates with the lower cam cylinder, the plate also tends to rotate and will rotate until stopped as hereinbefore described. Consequently during the oscillating rotary movements of the cylinders a similar movement is imparted to the plate. During the continuous rotary movement of the cylinders the ring moves to its limit in one direction and stays there.

Secured to the collar 103 is a curved guard 189. A similar curved guard 190, but somewhat shorter, is secured to the plate 102 as shown. During the continuous rotary movement of the cylinders, the annular plate is moved to close up the gap between the two guards so that in effect a continuous guard is formed. The function of this guard is to prevent the latches of the needles dropping too soon, and as such guards are commonly employed no specific description or illustration of the mode of operation is necessary.

During the oscillating rotary knitting the needle latches have to drop alternately at opposite sides of the knitting position. It will be noted that the movement of the knitting cylinders in the direction opposite to the arrow in Fig. 12 will at once open up a gap between the guards 189 and 190, providing proper space at the proper time to allow the latches of the needles to fall at that side of the knitting position.

As the mode of operation has been very fully described in connection with the description of the construction of the various parts, the general operation of the machine should be clearly understood without any further special general description thereof.

What I claim as my invention is:

1. In a knitting machine employing superimposed rotary cylinders provided with aligned vertical grooves, the combination with the lower cylinder of a surrounding cam wall provided with knitting cam grooves, a lower non-knitting groove and an upper non-knitting pathway about the upper cam groove; needle-carrying jacks provided with heels adapted to move along the grooves and pathway; and cam means between the upper knitting cam groove and the non-knitting pathway adapted to be positioned to engage jack heels to either draw them down from the said pathway to the groove or to throw them up from the groove to the pathway.

2. In a knitting machine employing superimposed rotary cylinders provided with aligned vertical grooves, the combination with the lower cylinder of a surrounding cam wall provided with knitting cam grooves, a lower non-knitting groove and an upper non-knitting pathway about the upper cam groove; needle-carrying jacks pro-

vided with heels adapted to move along the grooves and pathway; and cam means between the upper knitting cam groove and the non-knitting pathway adapted to be positioned to engage jack heels to either draw them down from the said pathway to the groove or to throw them up from the groove to the pathway, the upper heels of the jacks for half only of the circumference of the cylinder being long enough for engagement by the said cam means.

3. In a knitting machine employing superimposed rotary cylinders provided with aligned vertical grooves, the combination with the lower cylinder of a surrounding cam wall provided with knitting cam grooves, a lower non-knitting groove and an upper non-knitting pathway about the upper cam groove; needle-carrying jacks and non-transferring needles provided with heels adapted to move along the grooves and pathway; and cam means between the upper knitting cam groove and the non-knitting pathway adapted to be positioned to engage jack heels to either draw them down from the said pathway to the groove or to throw them up from the groove to the pathway, the upper heels of the jacks and non-transferring needles for half only of the circumference of the cylinder being long enough for engagement by the said cam means.

4. In a knitting machine employing superimposed rotary cylinders, the combination of a lower cylinder provided with vertical grooves; needle-carrying jacks slideable in said grooves each provided with two heels; a cam wall surrounding the cylinder provided with a lower non-knitting groove and an upper non-knitting pathway and a knitting cam groove for each heel of a jack in part paralleling respectively the said non-knitting groove and pathway and each having double knitting cams; an inclined cam movable to and from a position to engage jack heels and crossing the lower knitting groove and non-knitting groove adapted to project the jacks above the normal non-knitting position; an inclined plane placed to engage the same heels as the said cam to return said jacks to the normal non-knitting position, a gap being formed in the pathway aforesaid to permit of the upward movement and return of the upper jack heels.

5. In a knitting machine employing superimposed rotary cylinders, the combination of a lower cylinder provided with vertical grooves; needle-carrying jacks slideable in said grooves each provided with two heels; a cam wall surrounding the cylinder provided with a lower non-knitting groove and an upper non-knitting pathway and a knitting cam groove for each heel of a jack in part paralleling respectively the said non-

knitting groove and pathway and each having double knitting cams; an inclined cam movable to and from a position to engage jack heels and crossing the lower knitting groove and non-knitting groove adapted to project the jacks above the normal non-knitting position; an inclined plane placed to engage the same heels as the said cam to return said jacks to the normal non-knitting position, a gap being formed in the pathway aforesaid to permit of the upward movement and return of the upper jack heels; cam means movable in said gap immediately forward of the knitting cams for directing the heels of jacks or needles from the knitting groove to the pathway and vice versa, the lower grooves below said cam means being in communication.

6. In a knitting machine employing superimposed rotary cylinders, the combination of a lower cylinder provided with vertical grooves for needles and jacks provided each with two heels; a cam wall surrounding the cylinder provided with a lower non-knitting groove, an upper non-knitting pathway and a knitting cam groove for each heel of a jack or needle in part paralleling the said non-knitting groove and pathway and each having double knitting cams, gaps being provided to form communications between the knitting cam grooves and the non-knitting groove and pathway respectively, said gaps being located above the adjacent ends of the double cams; a pivoted gate in the upper gap adapted to swing from side to side as contacted by heels to direct them down one or the other knitting cam; a dog having a notched end pivoted below the lower gap so as to swing from one of the lower knitting cams to the other, in either position the notch in its end lying in the path of heels passing toward the opposite cam, whereby a jack or needle having its lower heel so engaging in the notch will be raised so that its upper heel is lifted past the pivoted gate through the upper gap to the level of the non-knitting pathway and its lower heel through the lower gap to the level of the non-knitting groove.

7. In a knitting machine employing superimposed rotary cylinders, the combination of a lower cylinder provided with vertical grooves for needles and jacks provided each with two heels; a cam wall surrounding the cylinder provided with a lower non-knitting groove, an upper non-knitting pathway and a knitting cam groove for each heel of a jack or needle in part paralleling the said non-knitting groove and pathway and each having double knitting cams, gaps being provided to form communications between the knitting cam grooves and the non-knitting groove and pathway respectively, said gaps being located above the adjacent ends of the double cams; a pivoted gate in the

- upper gap adapted to swing from side to side as contacted by heels to direct them down one or the other knitting cam; a finger pivoted above the lower gap provided 5 with a forked end of sufficient width to engage two heels at a time, said end being normally above the non-knitting groove; and means whereby when the cylinder is oscillatingly rotated, the finger is partly rocked 10 immediately following a change in the direction of motion to bring its lower end into the path of heels traveling in the non-knitting groove, the pressure of said heels continuing the rocking movement of the finger 15 to move said heels towards the opposite lower knitting cam and the upper heels of the jacks or needles so moved into engagement with the pivoted gate so that said heels are guided down the corresponding upper 20 knitting cam.
8. In a knitting machine employing superimposed rotary cylinders, the combination of a lower cylinder provided with vertical 25 grooves for needles and jacks provided each with two heels; a cam wall surrounding the cylinder provided with a lower non-knitting groove, an upper non-knitting pathway and a knitting cam groove for each heel of a jack or needle in part paralleling the said non-knitting groove and pathway and each 30 having double knitting cams, gaps being provided to form communications between the knitting cam grooves and the non-knitting 35 groove and pathway respectively, said gaps being located above the adjacent ends of the double cams; a pivoted gate in the upper gap adapted to swing from side to side as contacted by heels to direct them down one or the other knitting cam; a dog 40 having a notched end pivoted below the lower gap so as to swing from one of the lower knitting cams to the other, in either position the notch in its end lying in the path of heels passing toward the opposite cam, whereby a jack or needle having its 45 lower heel so engaging in the notch will be raised so that its upper heel is lifted past the pivoted gate through the upper gap to the level of the non-knitting pathway and its lower heel through the lower gap to the level of the non-knitting groove; and spring 50 means tending to snap the dog to its limit of movement in either direction after it has been moved partway.
9. In a knitting machine employing superimposed rotary cylinders, the combination of a lower cylinder provided with vertical 55 grooves for needles and jacks provided each with two heels; a cam wall surrounding the cylinder provided with a lower non-knitting groove, an upper non-knitting pathway and a knitting cam groove for each heel of a jack or needle in part paralleling the said non-knitting groove and pathway and each 60 having double knitting cams, gaps being provided to form communications between the knitting cam grooves and the non-knitting groove and pathway respectively, said gaps being located above the adjacent ends of the double cams; a pivoted gate in the upper gap adapted to swing from side to side as contacted by heels to direct them down one or the other knitting cam; a dog having a notched end pivoted below the lower gap so as to swing from one of the lower knitting cams to the other, in either 65 position the notch in its end lying in the path of heels passing toward the opposite cam, whereby a jack or needle having its lower heel so engaging in the notch will be raised so that its upper heel is lifted past the pivoted gate through the upper gap to the level of the non-knitting pathway and its lower heel through the lower gap to the level of the non-knitting groove; a finger pivoted above the lower gap provided with a forked end of sufficient width to engage two 70 heels at a time, said end being normally above the non-knitting groove; and means whereby when the cylinder is oscillatingly rotated, the finger is partly rocked 75 immediately following a change in the direction of motion to bring its lower end into the path of heels traveling in the non-knitting groove, the pressure of said heels continuing the rocking movement of the finger to move said heels toward the opposite lower knitting cam and the upper heels of the jacks or needles so moved into engagement with the pivoted gate so that said heels are guided down the corresponding upper 80 knitting cam; and spring means tending to snap the finger to its limit of movement in either direction after it has been moved part way.
10. In a knitting machine employing superimposed rotary cylinders, the combination of a lower cylinder provided with vertical 85 grooves for needles and jacks provided each with two heels; a cam wall surrounding the cylinder provided with a lower non-knitting groove; an upper non-knitting pathway and a knitting cam groove for each heel of a jack or needle in part paralleling the said non-knitting groove and pathway and each 90 having double knitting cams, gaps being provided to form communications between the knitting cam grooves and the non-knitting groove and pathway respectively, said gaps being located above the adjacent ends of the double cams; a pivoted gate in the upper gap adapted to swing from side to side as contacted by heels to direct them down one or the other knitting cam; a dog having a notched end pivoted below the lower gap so as to swing from one of the lower knitting cams to the other, in either 95 position the notch in its end lying in the path of heels passing toward the opposite cam, whereby a jack or needle having its lower heel so engaging in the notch will be raised so that its upper heel is lifted past the pivoted gate through the upper gap to the level of the non-knitting pathway and its lower heel through the lower gap to the level of the non-knitting groove; a finger pivoted above the lower gap provided with a forked end of sufficient width to engage two 100 heels at a time, said end being normally above the non-knitting groove; and means whereby when the cylinder is oscillatingly rotated, the finger is partly rocked 105 immediately following a change in the direction of motion to bring its lower end into the path of heels traveling in the non-knitting groove, the pressure of said heels continuing the rocking movement of the finger to move said heels toward the opposite lower knitting cam and the upper heels of the jacks or needles so moved into engagement with the pivoted gate so that said heels are guided down the corresponding upper 110 knitting cam; and spring means tending to snap the finger to its limit of movement in either direction after it has been moved part way.

diately following a change in the direction of motion to bring its lower end into the path of heels traveling in the non-knitting groove, the pressure of said heels continuing the rocking movement of the finger to move said heels toward the opposite lower knitting cam and the upper heels of the jacks or needles so moved into engagement with the pivoted gate so that said heels are guided down the corresponding upper knitting cam, the aforesaid dog having a gap formed in one side for the passage of heels.

11. In a knitting machine, the combination of a main shaft; a countershaft parallel thereto; two sprocket wheels loose on the countershaft each having a clutch member connected therewith; a clutch member on the countershaft intermediate the sprocket wheels rotatable with the shaft but slideable thereon; sprocket gearing between one of said sprocket wheels and the main shaft; a sprocket chain engaged with the other sprocket wheel; an idler sprocket supporting said chain; a slotted cross bar transverse of the chain connected to one side thereof; guide rods on which said bar is supported; and a pin secured to a sprocket wheel of the gearing between the main shaft and the first mentioned sprocket wheel on the countershaft adapted to work in said cross bar; a vertical shaft geared to the countershaft; knitting cylinders geared to the vertical shaft; a cam drum suitably actuated; and means controlled by the cam drum for shifting the aforesaid sliding clutch member.

12. In a knitting machine, a countershaft; a vertical shaft geared thereto; knitting cylinders geared to said vertical shaft; two sprocket wheels loose on the countershaft; means for imparting a continuous rotary movement to one sprocket wheel; means for imparting oscillating rotary movement to the other sprocket wheel; a clutch member rotatable with the shaft but slideable therein

between the two sprocket wheels; clutch members on said sprocket wheels with which said sliding clutch member may be engaged; a shifter suitably engaged with said sliding clutch member; a bar to which said shifter is secured, said bar being slideable on the frame parallel to the countershaft; two arms secured to the bar at different levels; a sleeve slideable on but rotatable with the vertical shaft and embraced by said arms; cam projections on said sleeve adapted by the raising and lowering of the sleeve to be brought into a position to engage either arm; a rocking lever adapted to shift said sleeve; and a cam drum adapted to actuate said lever.

13. In a knitting machine, the combination of a main driving shaft; two pulleys for driving the same; a sliding belt shifter for moving a belt from one pulley to another; two spring actuated plungers, normally retracted, and carried by said shifter; a slide movable on said shifter; inclined planes on said plungers to project them and arranged so that movement of the slide in one direction projects one plunger and movement of the slide in the opposite direction projects the other plunger; a rock shaft; connections between the rock shaft and slide for operating the latter; a suitably actuated cam drum; means whereby the said drum rocks the said rock shaft alternately in opposite directions; a countershaft driven from the main shaft; and a cam secured to said shaft having inclined cam faces formed thereon, one at each side, so adapted to engage one of said plungers when projected to move the shifter in one direction and the other to move it in the other direction.

Signed at Georgetown, Canada, this 11th day of July, 1916.

JOHN A. RUSH.
